FOLDING CHAIR

Clarence F. Benjamin, Devon, Conn.

Application February 1, 1939, Serial No. 253,975

9 Claims. (Cl. 155—117)

This invention relates to new and useful improvements in folding chairs, and has particular relation to the porch, beach or lawn type of folding chair.

An object of the invention is to provide a chair of the type indicated which is readily adjustable to the comfort of the user while the latter remains seated in the chair.

Another object is to provide a chair of the character mentioned which is easy to get into and out of, and which provides a comfortable seat portion together with leg rests which while constantly available for use do not interfere with a user entering or leaving the chair, and which are so constructed and arranged that they may or may not be used as desired without the user being required to rise from the chair to change from use of the chair without using these rests, or to employ these rests as desired.

A further object is to provide a folding chair of light weight and sturdy construction, including a minimum of parts, and which may be readily and quickly opened for use and folded to occupy a minimum of space for storage or transportation.

Other objects and advantages will become apparent from a consideration of the following detailed description taken in connection with the accompanying drawing wherein satisfactory embodiments of the invention are shown. However, it is to be understood that the invention is not limited to the details disclosed but includes all such variations and modifications as fall within the scope of the invention.

In the drawing:

Fig. 1 is a side elevational view of the chair of the invention open for use;

Fig. 2 is a top plan view of the chair as shown in Fig. 1 but with a portion of the canvas seat omitted;

Fig. 3 is a side elevational view showing the chair folded;

Fig. 4 is a plan view showing a detail of construction relating to the tensioning of the under canvas seat of the chair;

Fig. 5 is a view at right angles to Fig. 4;

Fig. 6 is an enlarged detail elevational view showing the construction employed in bracing the frame of the chair;

Fig. 7 is a detail sectional view taken as along the line 7—7 of Fig. 6;

Fig. 8 is an elevational view taken as looking from the left in Fig. 6;

Fig. 9 is a view similar to Fig. 1 but on a smaller scale and showing a modification;

Fig. 10 is a detail plan view showing a portion of the chair of Fig. 9;

Fig. 11 is a detail view of a portion of the construction of Figs. 9 and 10; and

Fig. 12 is a view looking from the right of Fig. 11.

Referring in detail to the drawing and at first more particularly to the construction shown in Figs. 1 through 8, at 10 is generally indicated my improved folding chair and the same includes a supporting structure comprising front and rear leg frames A and B respectively, a back frame C and a leg or foot rest D. Front leg frame A includes leg members 11 and 12 and a brace member 13 extending between and connected with such legs in a manner to be described. Leg frame B comprises a pair of legs 14 and 15 each provided with a longitudinally extending slot 16 and with a reinforcement 17 beyond the lower end of such slot to prevent splitting of the leg.

The front and rear leg frames A and B incline toward one another, and the upper ends of the legs 11 and 12 are pivotally connected with the upper ends of the legs 14 and 15 respectively by any suitable means such for example as a nut and bolt 18. Thus it will be seen that the leg frames are connected for relative folding movements.

Back frame C comprises side frame members 19 and 20 having pivotal connection at their lower ends on a connecting means or bar 21 extending transversely of the chair. The upper ends of the members 19 and 20 are connected by a brace piece 22 extending between and through the members. Strengthening blocks 23 are shown secured against the inner sides of the upper end portions of the members 19 and 20 as by nut and bolt means 24 and extend along these members a sufficient distance to give a long enough bearing to secure the proper bracing effect. If preferred these blocks may be located on the outer sides of members 19 and 20. In this case the bar 22 is made sufficiently longer to extend through these blocks. With these blocks on the outer sides of the side members more space is provided for mounting a shade on the bar 22 if one is desired. It is noted that the end portions of the members 19 and 20 are split as at 25 and the outer ends of the split portions connected by nut and bolt means 26 so they can be clamped on the bar 22 to hold it against turning for a purpose later to be described.

Foot or leg rest D comprises a pair of similar elongated members 27 and 28 the inner end of each of which is secured to the connecting means

or bar 21, the intermediate portion of each of which rests on the rigid brace 13, and the outer portion of each of which is widened to provide foot and leg rest portions 29. The inner ends of the members 27 and 28 are secured to the connecting bar 21 in the same manner, and the details of such connection are shown in Figs. 4 and 5.

In their upper faces toward their inner ends the members 27 and 28 are provided with transversely extending grooves 30 to receive the under half of the bar 21. Disposed over the received portions of such bar are blocks 31 having grooves 32 in their under sides to receive the upper portions of the said bar. Bolts 33 pass through the members 27 and 28 at each side of the groove 30 therein and through the blocks 31, and on tightening of the nuts 34 on said bolts the blocks will be drawn against the bar 21 and securely clamp it against turning movement relative to the members 27 and 28.

The members 27 and 28 pass over the brace 13 adjacent the ends of the latter and hinges 35 are secured to the under sides of the said members and to the brace. Thus the members are connected with the brace but may have folding movements relative thereto.

Extensions of the means 21, which extensions may be for example in the form of lag screws 36, pass through the slots 16 in the legs of the frame B, and while the end portions of the means might be passed through the slots lag screws may be used since they may be of relatively small diameter whereby the slots may be kept narrow. The lag screws are movable along the slots whereby the back may be adjusted, and also to permit of the folding of the chair as will appear.

An underseat 37 in the form of a piece of canvas or other flexible material is secured at its forward end to the brace 13 as by tacks or the like, and the rear end of such seat is secured to the connecting means or bar 21 in any suitable manner. The said underseat may be kept to any desired degree of tautness by adjustment of the means 21. Thus to adjust the under seat the means 21 is released by backing off the nuts 34 and thereafter the bar is turned about its longitudinal axis to wrap a portion of the material of the seat about or unwrap it from the bar and then the nuts 34 are again tightened to hold the bar against turning movement.

The chair includes a seat and back formed by a length of canvas or other flexible material 38 secured at its forward end to the brace 13 and extending over the underseat 37 and upwardly of the back frame C. The other or upper end of the material 38 is secured to the cross piece or bar 22 in any suitable manner. Thus the material 38 provides the chair with a seat portion 39 and a back portion 40. This seat and back may be tightened by loosening the nuts of the nut and bolt means 26 then turning the piece 22 about its longitudinal axis to wind any desired portion of the material 38 thereon. It may be loosened by turning in the opposite direction to unwind it from the bar. Thereafter the nuts on means 26 are tightened to hold the cross piece 22 against turning movement relative to the frame C.

Leather, canvas or other flexible straps 41 provide arm rests at the respective sides of the chair. The inner ends of these straps are secured to the intermediate portions of the members 19 and 20 of the frame C as by means of the clevis 42 and the outer or forward ends of the straps are adjustably secured to the supporting structure of

the chair as by the buckles 43 secured to the legs of the frame A. The straps may be adjusted through the buckles to adjust the angle of inclination of the back frame C, and such adjustments may be made while the person making the adjustment is seated in the chair.

The two seats or the double seat provided by the invention adds materially to the comfort of the chair since with this construction the seat is straighter and maintained in a more natural and comfortable position and does not sag as it would with a single seat. The foot rests 29 being spaced apart a woman may walk between them to sit in the chair without the foot rests interfering with her skirt. A person using the chair does not need to use the foot rests and the latter are not in the way while the chair is in use with the feet resting on the floor or while a person is entering or leaving the chair. The feet and legs may be moved from the rests to the floor or vice versa to change position without the user being required to leave the chair to fold or adjust the rests.

Figs. 6, 7 and 8 show the details of the connection between the brace 13 and the front legs 11 and 12 of the chair. In such figures it will be noted that the ends of the brace are reduced providing tongues 44 entering recesses in the inner sides of the legs whereby the brace and legs are mortised together. In addition bolts 45 are passed through the legs from the outer sides thereof and enter the end portions of the brace. Inwardly of its ends the brace is provided with openings 46 permitting of the mounting of nuts 47 on the inner ends of the bolts. On tightening of the nuts 47 the legs 11 and 12 and the brace 13 are drawn tightly together providing a very rigid structure.

The angle of inclination of the foot rests 29 and back C may be changed by adjusting the relative angle of legs 11 and 14 by moving the bar 21 and members 36 to different positions along the slots 16. After adjustment the weight of the user and engagement of the lower ends of the legs on the floor or ground will retain them in adjusted positions. These adjustments can be made while the user is sitting in the chair. One can do this by moving his body forward reaching rearwardly with the hands and pulling the rear legs 14 forward thus causing the rod 21 to slide down in slots 16 and raising the leg rests 29.

Figs. 9 and 10 show a slightly modified construction wherein the chair is generally designated 50 and includes a front leg frame A', a back frame C' and a foot rest frame D' all of the construction of the frames A, C and D previously described. The rear leg frame B' of the chair 50 includes a brace 51 extending between and connecting the rear legs 52 and 53 which it is noted are not slotted as are the legs 14 and 15 of the form first described. The brace 51 is connected to the legs 52 and 53 in the manner shown in Figs. 6, 7 and 8.

A connecting means or bar 54 extends transversely of the chair 50 and replaces the connecting means 21 of the chair 10. The rear end of the foot rest frame D' is connected to the means 54 through the clamping means including the blocks 31 and the bolts 33 and nuts 34 while the lower end of the back frame C' is pivotally connected with the said means. Means 54 is of such length as to project beyond the sides of the legs 52 and 53 and in fact when the chair is set up for use has its end portions 58 resting on the upper side of such legs as shown. These end

portions may be formed with a groove 59 to receive a split spring ring 60 so it projects beyond the surface of bar 54 just outside the side members 19 as shown in Figs. 10, 11 and 12 to hold them from sliding off the ends of the bar.

The ends of the brace 51 are mortised into the legs 52 and 53 and the legs and brace are clamped together by the nut and bolt means 55 and 56. From Fig. 10 it will be clear that the bolts 55 pass through the legs from the outer sides thereof and that the brace 51 is provided adjacent its ends with openings 57 whereby the nuts may be applied to the bolts after which on tightening of the nuts on the bolts the brace and legs are drawn tightly together providing a rigid structure. Thus it will be seen with the exceptions of the use of the brace 51 and the extension of the connecting means 54 and the disposing of the same on the upper edges of the legs 52 and 53 the construction of the chair of Figs. 9 and 10 is the same as that of Figs. 1 through 8.

The angle of inclination of the leg rests and back in this chair can also be adjusted as in the first form by moving the end portions 58 of bar 54 to different positions along the top of the legs 52. The weight of the user and engagement of the ends of the legs on the floor or ground retains them in adjusted positions. These adjustments can be made while the user is sitting in the chair.

The chairs fold much alike. In folding chair 10 the leg frames A and B are swung toward one another about the pivoting means 18 and the connecting means 21 moves downwardly, being guided by the slots 16. During this time the frame D is rocking on its hinges 35 and its inner end together with the lower end of the back frame C is moving with the connecting means 21. Thus the leg frames fold one partly within the other while the back frame C folds partly into the rear leg frame and the foot rest members are partly within the leg frames, but being of greater length projects beyond their forward ends.

In folding chair 50 the action is about the same except that movement of the connecting means 54 is not controlled by slots. The flexible materials forming the double seat and back in the disclosed constructions will not interfere with the folding of the chairs, and the same is true with respect to the flexible straps 41 comprising arm rests and means for adjusting the relation between the seat and back.

The chairs disclosed are fully braced laterally since the chair 10 has cross braces 13, 21 and 22 while the chair 50 has the cross braces 13 and 22, and further has the brace 51. The chairs are easily folded and unfolded, are rigid and will withstand hard usage, are easy to enter and to leave, and the back and seat may be adjusted to the convenience of the user while the latter is seated in the chair. Such adjustment takes place by tightening or loosening of the strap-like arm rests 41. Also, the inclination of the foot rests may be varied as described.

Having thus set forth the nature of my invention, what I claim is:

1. In a folding chair, front and rear leg frames each comprising a pair of leg members, said frames inclining toward one another, means pivotally connecting the upper ends of the rear leg members to the upper ends of the front leg members, a rigid brace connecting said front leg members intermediate their ends, foot rest members and a back frame, means comprising a rear cross

brace pivotally connecting the lower end of the back rest frame with the rear ends of the foot rest members and supported on said rear leg members, a flexible underseat connected at its respective ends with the last mentioned means and said rigid brace, means hingedly connecting intermediate portions of the foot rest members with said rigid brace, an upper brace connecting the upper portions of the back rest frame members, a flexible seat and back means located over the underseat and connected at its respective ends to said rigid and upper braces, said rear brace being rotatable relative to said foot rest members to adjust the length of the underseat, means for clamping the rear brace in adjusted position, and side arm portions connecting the back frame with said pivotally connected leg frames.

2. In a folding chair, a supporting structure comprising pivotally connected front and rear legs, a rigid brace extending between and connected with said front legs, foot rest members, a back frame, means comprising a rear cross brace pivotally connecting the rear ends of the foot rest members with the lower end of the back frame and movably supported on said rear legs, said foot rest members projecting forwardly and having their intermediate portions resting on and hinged to said rigid brace, adjustable arm rests connected with said back frame and said supporting structure, and a seat and back for said chair comprising a flexible member connected at its respective ends with said rigid brace and said back frame, a flexible underseat connecting the rigid and rear braces, said rear brace being rotatable relative to the foot rest members to adjust the length of the underseat, and means for clamping this brace in adjusted positions.

3. In a folding chair, a supporting structure comprising front and rear legs inclined in opposite directions and pivotally connected at their upper ends, a rigid brace extending between said front legs, said brace comprising a member having end portions of considerably greater width than thickness, means rigidly connecting the ends of said brace to the front legs and with the width of the brace extending longitudinally along said legs, foot rest members, a back frame, means pivotally connecting the rear ends of the foot rest members with the lower end of the back frame and supported on said rear legs, said foot rest members projecting forwardly and having their intermediate portions resting on and hinged to said rigid brace, adjustable flexible arm rests connected with said back frame and said supporting structure adjacent the pivotal connection between the legs, a seat and back for said chair comprising a flexible member connected at its respective ends with said brace and said back frame, and said foot rest members beyond said rigid brace comprising a pair of spaced members between which a user may enter to sit in the chair.

4. In a folding chair, a supporting structure comprising pivotally connected front and rear legs, a rigid brace extending between and connected with said front legs, foot rest members, a back frame, means pivotally connecting the rear ends of the foot rest members with the lower end of the back frame and movably supported on said rear legs, said foot rest members projecting forwardly and having their intermediate portions hinged to said rigid brace, adjustable means connecting the back frame with said supporting structure, a seat and back for said chair comprising a flexible member connected at its respec-

tive ends with said brace and said back frame, a flexible underseat connected at its forward end with said brace and at its rear end with said means connecting the back and foot rest members, said last mentioned means being turnable relative to said members to adjust the tension of the material of said underseat, and means for securing said connecting means against casual turning movement.

5. In a folding chair, a supporting structure comprising pivotally connected front and rear legs, a rigid brace extending between and connected with said front legs, foot rest members, a back frame, means pivotally connecting the rear ends of the foot rest members with the lower end of the back frame and movably supported on said rear legs, said foot rest members projecting forwardly and having their intermediate portions hinged to said brace, adjustable arm rest means connecting the back frame with said supporting structure, a seat and back for such chair comprising a flexible member connected at its respective ends with said brace and said back frame, a flexible underseat connected at its forward end with said brace and at its rear end with said means connecting the back and foot rest members, said last mentioned means being turnable relative to said members to adjust the tension of the material of said underseat, and means on at least one of said foot rest members and embracing said connecting means and adjustable to tightly clamp the same to secure it in an adjusted position.

6. In a folding chair, a supporting structure including oppositely inclined front and rear legs, means pivotally connecting said front and rear legs at their upper ends for relative folding movements, a back frame resting at its lower end on said rear legs and including a lower cross member, a rigid brace connecting said front legs, a seat and back connected at its respective ends with said brace and said back frame, side members hinged to the brace and pivotally connected to the lower end of the back frame, flexible strap and buckle means at each side of said chair and connecting an intermediate portion of the back frame with said supporting structure for adjustment of the back frame relative to such structure, and a flexible under-seat connected at its forward end with said brace and at its rear end with said cross member, and said cross member being turnable relative to the side members to adjust the tension of the material of said under-seat.

7. In a folding chair, a supporting structure including front and rear legs, means connecting said front and rear legs for relative folding movements, a back frame resting at its lower end on said rear legs, a brace connecting said front legs, side members hinged to the brace and pivotally connected to the lower end of the back frame,

said back frame comprising side members and a connecting piece extending between said side members adjacent each of their ends, a flexible seat and back connected at its respective ends with said brace and said connecting piece at the outer end of the frame, said connecting piece being turnable relative to the remainder of the back frame to adjust the length of said flexible seat and back, means to secure said connecting piece against turning movement after adjustment, and a flexible under-seat connected at its forward end with said brace and at its rear end with the connecting piece at the lower end of the frame, said latter connecting piece being turnable to adjust the tension of the material of said under-seat.

8. In a folding chair, a supporting structure comprising front and rear legs and means connecting said legs for relative folding movements, a rigid brace means extending between said front legs, said brace comprising a member having end portions of considerably greater width than thickness, means rigidly connecting the ends of said brace to the front legs and with the width of the brace extending longitudinally along said legs, foot rest members, a back frame, means pivotally connecting the rear end of said foot rest members with the lower end of the back frame and supported on said rear legs, said foot rest members projecting forwardly and having their intermediate portions resting on said rigid brace, means hinging said intermediate portion to said brace, adjustable arm rest means connected with said back frame and said supporting structure, and a seat and back for said chair comprising a flexible member connected at its respective ends with said brace and said back frame.

9. In a folding chair, a supporting structure comprising front and rear legs inclining toward one another and pivotally connected at their upper ends, a rigid brace means extending between said front legs, said brace comprising a member having end portions of considerably greater width than thickness, means rigidly connecting the ends of said brace to the front legs and with the width of the brace extending longitudinally along said legs, a similar rigid brace extending between and connecting said rear legs, foot rest members, a back frame, means connecting the rear end of foot rest members with the lower end of said back frame and resting on the upper edges of said inclined rear legs, said foot rest members projecting forwardly and having their intermediate portions hinged to said first named rigid brace, flexible arm rests connecting the back frame and the upper ends of the legs, and a seat and back comprising a flexible member connected at its respective ends with said brace connecting said front legs and with said back frame.
